UNITED STATES PATENT OFFICE.

LA VERNE W. NOYES, OF CHICAGO, ILLINOIS.

WINDMILL.

SPECIFICATION forming part of Letters Patent No. 609,457, dated August 23, 1898.

Application filed May 26, 1897. Serial No. 638,197. (No model.)

To all whom it may concern:

Be it known that I, LA VERNE W. NOYES, a citizen of the United States, residing at Chicago, in the county of Cook and State of Illinois, have invented a certain new and useful Improvement in Windmills, of which the following is a full, clear, concise, and exact description, reference being had to the accompanying drawings, forming a part of this specification.

My invention relates to a windmill.

My object is to provide an improved construction of vane-support and to provide a simple and effective furling device and brake for bringing the wheel to rest. The tail-bone is formed straight between the pivot and the vane, and in order that it may not interfere with the driving-train when out of the wind the pivot for the tail-bone is provided upon an arm or bracket extending outward from the frame to support the tail-bone in position beyond the path of travel of the driving-gear. The end of the tail-bone is resiliently connected with the furl-lever by means of a coiled spring, and the vane is locked out of the wind by means of a locking-rod. The brake comprises a brake-disk adapted to engage the rim of the wheel-spider, the brake-disk being threaded upon a rotatable ring, which in turn is threaded upon a stationary part of the frame, and the ring is rotated to advance and retract the brake-disk by means of a weight which is raised and lowered by the furl-lever, thus throwing on and off the brake as the furl-lever is moved to throw the wheel out of and into the wind.

Referring to the accompanying drawings, Figure 1 is an end view of the mill in elevation. Fig. 2 is a side view thereof. Fig. 3 is a detail view of the brake and furling-lever. Fig. 4 is a plan view of the mill. Fig. 5 is a detached view of the brake-disk. Fig. 6 is a sectional view thereof on line 6 6, Fig. 5. Fig. 7 is a detached view of the brake-ring. Fig. 8 is a sectional view thereof on line 8 8, Fig. 7. Fig. 9 is a sectional view of the shaft-bearing. Fig. 10 is a sectional view showing the parts of the brake assembled.

Like letters refer to like parts in the several figures.

The hub or spider *a* of the wind-wheel is

carried on a shaft or axle *b*, journaled in the bearing-sleeve *a'*. Upon the opposite end of the shaft is carried the pinion *b'*, which meshes with the gear-wheel *b*², journaled upon the shaft or stud *b*³, carried on the frame of the machine. The end of the pitman-rod *c* is journaled to a crank-pin on the wheel *b*² and is journaled at the opposite end to a pin on the link *c'*, having a bifurcated end *c*³ *c*², journaled upon the rod or shaft *c*⁴, carried in bearing *c*⁴. To the pin on the link *c'* is also journaled the end of the pump-rod *c*⁵. As the main shaft rotates motion is transmitted to the gear-wheel *b*² and from thence through the pitman-rod to the link *c'*, causing the same to vibrate to reciprocate the pump-rod.

Upon the standard or frame is provided an extending arm or bracket *d*, to the end of which the upper member or tail-bone *e* of the vane is pivoted, while the lower member or tail-bone brace *d*² is pivoted upon an arm or bracket *d*¹, likewise extending from the frame. The lower pivot is more remote from the frame than the upper pivot, so that the vane when in the wind is elevated and will return to the position out of the wind by its own weight when released. Upon the frame is carried a projecting arm or stop *d*³, which limits the inward movement of the vane when swinging out of the wind. The lengths of the arms *d* and of the stop *d*³ are such that when the vane is out of the wind and lies parallel with the wheel the bones of the vane rest beyond and out of the path of travel of the driving train or gear of the wheel. By this construction the tail-bone may be made perfectly straight between the pivot and the vane, and when out of the wind the tail-bone will not interfere with the driving-train.

The end of the tail-bone is bent downward and toward the wheel to form an inturned end *e*². To the end of the tail-bone is attached the coiled spring *f*, the opposite end of which is attached to the end of the arm *g'* of the furl-lever *g*, pivoted to the frame at *g*² and carrying an arm *g*³, to which is attached the furling rod or wire *g*⁴, which extends through the barrel of the frame alongside the pump-rod. To the end of the tail-bone is attached a rod *h*, which extends through the interior of the coiled spring *f* and rests against

the inner face of the brake-disk k when the wheel is out of the wind, the end of the rod resting in engagement with one of the vertical ridges $k' k'$ upon the said disk. The end 5 of the rod is held against the disk by engagement with the lug h' on the lower arm of the furl-lever, which limits the outward movement of the rod and presses the same against the face of the disk.

10 When it is desired to furl the mill, the furling-rod is pulled to rotate the furl-lever and move the arm g' thereof to the right, Figs. 1 and 4, thus moving the end of the coiled spring between the brake-disk and the end 15 of the brake-rod h to disengage the rod from the ridges on the brake-disk and permit the continued movement of the furl-lever to draw the wheel into the wind. When in the wind, the parts occupy the positions shown in dotted lines in Figs. 1 and 4. In throwing the mill out of the wind the furling-rod is released and the vane by its weight swings inward and thereby through the coiled spring draws the arm g' of the furl-lever to the left and carries 20 the end of the brake-rod h into engagement with the brake-disk, thus locking the vane in position and the wheel out of the wind.

25 I will now describe the brake for checking the rotation of the wheel when thrown out of the wind.

30 Upon the bearing-sleeve a' is provided a series of screw-threads $a^2 a^2$, with which engage threads on the interior of brake-ring l , carrying upon the exterior threads $l' l'$, which 35 engage corresponding threads in the bore of the brake-disk k . The periphery of the brake-disk is beveled and engages a correspondingly beveled flange or rim on the spider a of the wind-wheel, so that when the brake-disk is 40 moved into engagement with the rim of the spider the latter is brought to rest. The brake-disk k carries a downwardly-extending arm having a bifurcated end which straddles the bearing-sleeve a^3 to prevent the rotation 45 of the disk. Upon the brake-ring l is provided a lug l^2 , carrying a socket in which is clamped, by means of set-screw l^3 , the end of rod m , carrying upon the end a weight m' . The rod m rests upon and is supported by an 50 arm or lug m^2 on the arm g' of the furl-lever, and when the wheel is in the wind and the furl-lever is in the position shown in dotted lines in Fig. 1 the rod is elevated, thus rotating the brake-ring l to move the same away 55 from the wind-wheel, due to the screw-threads on the ring engaging with those on the bearing-sleeve. The rotation of the ring within the brake-disk in turn retracts the disk, due to the engagement of the threads on the ring 60 and disk. The brake-disk is thus maintained out of engagement with the rim of the spider and the wind-wheel is free to rotate. When the wheel is thrown out of the wind, the furl-lever assumes the position shown in full lines 65 in Figs. 1 and 4, thus lowering the rod m and rotating the brake-ring to advance the same toward the spider, and thereby advancing the

brake-disk into engagement with the rim of spider to brake the wheel and bring the same to rest.

Having described my invention, what I claim as new, and desire to secure by Letters Patent, is—

1. In a windmill the combination with the wind-wheel and the driving-train, of a tail 75 pivoted on the side of the driving-train opposite the wind-wheel, and having the end extended beyond the pivot, a pivoted furl-lever having the end moving between the wind-wheel and the driving-train, and a coiled 80 spring connecting the extended end of the tail and the furl-lever and passing between the wind-wheel and the driving-train, substantially as described.

2. In a windmill, the combination with the 85 wind-wheel and the driving-train, of a tail pivoted on the side of the driving-train opposite the wind-wheel and having the end extended beyond the pivot and bent laterally toward the wind-wheel, a pivoted furl-lever 90 having the end moving between the wind-wheel and the driving-train, and a coiled spring connecting the extended end of the tail and the furl-lever and passing between the wind-wheel and the driving-train, sub- 95 stantially as described.

3. In a windmill, the combination with a wind-wheel and the driving-train, of the tail pivoted on the side of the driving-train opposite the wind-wheel and having the end 100 extended beyond the pivot and bent or deflected laterally toward the wind-wheel, a furl-lever having the end moving between the wind-wheel and the driving-train, a coiled spring connecting the end of the furl-lever 105 and the extended end of the tail, a locking-rod attached to the end of the tail and passing through the interior of said coiled spring, and a locking face or abutment against which the end of said locking-pin rests when the 110 wheel is out of the wind, substantially as described.

4. In a windmill, the combination with the wind-wheel, of a pivoted tail having the end extended beyond the pivot, a locking-pin attached at one end to the extended end of said tail, and a locking face or abutment against which the opposite end of said locking-pin rests when the wheel is out of the wind, substantially as described.

5. In a windmill, the combination with the wind-wheel and a pivoted tail having the end extended beyond the pivot, of a furl-lever, a resilient connection, as a coiled spring, connecting the furl-lever and the extended end 125 of the tail, a locking-pin attached to the extended end of the tail, and a locking face or abutment against which the end of the locking-pin rests when the wheel is out of the wind, substantially as described.

6. The combination with a wind-wheel and a pivoted tail, of a furl-lever, a coiled spring connecting the tail and the furl-lever, a locking-pin attached to the tail and extending

through the interior of said spring, and a locking face or abutment adapted to be engaged by the pin when the tail is in position to hold the wheel out of the wind, substantially as described.

7. In combination, a pivoted tail, a furl-lever, a coiled spring connecting the same, a locking-pin attached to the tail and extending through the interior of the said spring, a locking-face, and a lug on the furl-lever for holding said pin against the locking-face, substantially as described.

8. In combination, a pivoted tail, a furl-lever having one arm connected with the furl-rod or wire, a coiled spring between the other arm and the tail, a locking-pin attached to the tail and extending through the interior of the spring, and a plate carrying ridges on the face for the engagement of said locking-pin, substantially as described.

9. In a windmill-brake, the combination with the wind-wheel, of the sleeve in which the wheel-shaft is journaled, a rotatable ring thereon, and a brake-disk for engaging the wheel threaded upon said ring, substantially as described.

10. A windmill-brake comprising a brake-disk for engaging the wheel, a rotatable ring upon which the disk is threaded and a support upon which the ring is threaded, substantially as described.

11. A windmill-brake comprising a brake-disk for engaging the wheel, a rotatable ring for advancing the same a weighted rod attached to the ring, and a lever for raising and lowering the rod, substantially as described.

12. A windmill-brake comprising a brake-

disk for engaging the wheel, a rotatable ring upon which the disk is threaded, a support upon which the ring is threaded, a weighted rod attached to the ring and a lever for raising and lowering the rod substantially as described.

13. In combination, the brake-disk, the rotatable ring, upon which the same is threaded, the support upon which the ring is threaded, the weighted rod attached to the ring and the furl-lever upon which the rod rests for raising and lowering the same as the furl-lever is moved back and forth, substantially as described.

14. In combination, the pivoted tail, the furl-lever, the coiled spring joining the same, the locking-rod passing through the spring, the brake-disk engaged thereby, the rotatable threaded ring supporting the brake-disk and the weighted rod attached to said ring and supported upon the furl-lever, substantially as described.

15. The combination with the sleeve for the main bearing, of the rotatable ring threaded thereon, the brake-disk threaded on said ring and carrying the downwardly-extending arms, and the bearing-sleeve for the counter-shaft straddled by said arms, substantially as described.

In witness whereof I have hereunto subscribed my name in the presence of two witnesses.
